UNITED STATES PATENT OFFICE

BERNARD C. BECKER, OF YORK, PENNSYLVANIA, ASSIGNOR TO THE YODER PENCIL COMPANY, OF CLEVELAND, OHIO, A CORPORATION OF OHIO

PENCIL

Application filed February 3, 1922. Serial No. 533,844.

This invention relates to instruments for writing, or more particularly to a writing device which might properly be placed in a class between lead pencils and fountain pens.

5 The object of this invention is to provide a pencil in which plastic or semi-fluid substance may be used for producing the lines in writing.

10 The necessary characteristics of this substance is that it will not run too freely and spread like a liquid, but should be soft so that it can be readily pressed through the hole of a small tube. Graphite or lampblack ground in linseed oil makes a suitable preparation for this purpose, and many of the coloring pigments may be similarly prepared for this purpose.

15 As a preferred embodiment of this invention, the line producing substance is carried in a chamber formed by the handle of the pencil, and means are provided for automatically feeding the substance to the point of the pencil, this feeding means being automatic in that it operates to force the writing substance upon the surface being written upon through the mere customary action of writing, no form of manipulation is required for feeding said substance other than that naturally employed for merely producing 20 writing with the ordinary pencil or fountain pen.

25 Other objects will be apparent from the following description, taken in connection with the accompanying drawings, forming a part hereof, and in which similar numerals refer to similar parts throughout the several views.

30 Fig. 1, is a longitudinal sectional view of Fig. 1, is a longitudinal sectional view of a pencil representing a practical embodiment of this invention.

35 Fig. 2, is an enlargement of the end 2 of Fig. 1, showing certain detail parts which are too small proportionally to be shown clearly in Fig. 1.

40 Fig. 3, represents an end view of Fig. 2.

45 Fig. 4, is an enlarged view of the tube shown at 4, Fig. 1, and forms an auxiliary container for carrying the writing substance.

50 Fig. 5, is a longitudinal sectional view of the pencil shown in Fig. 1, the same being

separated, and shows the plunger in initial position as when filling the pencil with writing fluid.

Fig. 6, is a longitudinal sectional view of the pencil shown in Fig. 1, and shows the plunger in the lowermost position it may attain through the action of the automatic feeding mechanism.

Fig. 7, represents the plunger, separate and distinct from the pencil.

In the following description of this invention it should be understood that where any part is described as being "fixed" to another, the same may be soldered thereto unless otherwise stated.

Referring to the drawing, 5 is a tubular casing forming a handle for the pencil and an enclosure for the feeding mechanism, the same being divided into two parts 6 and 7. Fixed to the handle part 6 is a threaded bushing 8 which is adapted to engage the internal threads in handle part 7 as shown in Figs. 1 and 6. Fitted free to slide in the bushing 8, is a cylinder 9, forming a chamber 10, and tapers into a slender tubular point 11. The handle part 6 also tapers to fit neatly around the tubular point 11, and guides the cylinder 9 in lengthwise movement. The cylinder 9 is normally held in the forward direction, indicated by the arrow 12, against the tapered portion of the handle part 6 as shown at 14, by the spring 15.

In the cylinder 9 is fitted a piston 16 which forms a part of the piston rod 17. Carried on the end of the piston 16 through the screw 18, is a washer 19 made of cork, or other suitable material to serve as a packing to seal the piston against leakage.

The piston 16 is provided with a cavity 20 which carries a ball 21, the same being adapted to wedge between the inclined surface 22 and the wall of the cylinder 9; this prevents movement of the piston 16 relative to the cylinder 9, in the rearward direction indicated by the arrow 23. The spring 24 is adapted to normally hold the ball 21 in wedging position as shown.

To move the ball 21 out of wedging position and thereby cause the same to be in-

operative, I provide a sleeve 31, which fits free to slide on the piston 16 and piston rod 17. The hole 32 in the wall of the sleeve 31, allows the ball 21 to find the clamping position under the influence of spring 24, but when the sleeve 31 is moved in the direction indicated by the arrow 23 relative to the piston rod 17, it will move the ball 21 in the same direction against the action of the spring 24, and under this condition no wedging action of the ball 21 can occur and the piston 16 may be moved in either direction with ease.

Fixed to the handle part 7 is a bushing 25, into which is fitted free to slide, a tubular casing 26. This casing is enlarged and projects through the head end 28 of the handle part 7 as shown at 27. The spring 29 normally holds the tubular casing 26 in the forward position as shown in the drawing, the flanged end 30 bearing against the bushing 25.

The bushing 25 is provided with a cavity 33 which carries a ball 34, the same being adapted to wedge between the inclined surface 35 and the piston rod 17; this prevents movement of the piston rod 17 in the rearward direction indicated by the arrow 23. The spring 36 is adapted to normally hold the ball 34 in wedging position as shown.

A hole 37 is provided in the wall of the tubular casing 26, to allow the ball 34 to find the clamping position under the influence of the spring 36, but when the tubular casing 26 is moved in the direction indicated by the arrow 12 relative to the handle part 7 it moves the ball 34 in the same direction against the action of the spring 36, and under this condition no wedging action of the ball 34 can occur and the piston rod 17 may be moved in either direction with ease.

The cylinder 9 is provided with an enlarged bore 38 which is adapted to receive a tubular container, the object of which is to provide a convenient method for filling the pencil with writing substance.

Fig. 4 represents this tubular container in a form suitable to be placed on the market. It comprises a tube 4 of suitable size to fit the enlarged bore 38 of the pencil, and is provided with removable caps 39. The tube is completely filled with the writing substance indicated at 40.

For refilling the pencil with writing substance, the handle parts 6 and 7 are separated, and the plunger as represented in Fig. 7 is removed from the cylinder 9. After removing the caps 39, the tube 4 filled with the writing substance is then placed in the enlarged bore 38 of the cylinder 9, this enlarged bore 38 may be considered as a primary chamber for the writing substance, as carried by the auxiliary container formed by tube 4; and the chamber 10, as a second-

ary chamber which according to my preferred construction carries the writing substance when the pencil is in normal writing condition. The plunger is then entered in the tube 4 as shown in Fig. 5, and moved forward in the direction indicated by the arrow 12; this forces the writing substance from the tube 4 down into the secondary chamber 10. The handle parts 6 and 7 are then screwed together and the pencil is ready for writing.

While writing is progressing the operation of this pencil is as follows:

The piston 16 is normally held from moving in the rearward direction as indicated by the arrow 23, by the ball 34 through the rod 17. The cylinder 9 is free to move in this direction against the action of the spring 15. Through the action of writing the smooth spherical end 42 of the pencil is moved with ordinary writing pressure over the paper; thereby causing the cylinder 9 to move inward in the direction indicated by the arrow 23; reducing the volume of the chamber 10; and forcing the writing substance out through the hole 43 upon the paper. This action continues as long as a line is being produced, and the cylinder 9 continues to move inward at a proportional rate relative to the quantity of writing substance permitted to escape through the hole 43.

Whenever the end 42 is raised from the paper, for instance, between making words or characters; the spring 15 moves the cylinder 9 forward to the original position. In this forward movement of the cylinder 9, the piston 16 with the piston rod 17 are also moved forward, this being accomplished through the wedging action of the ball 21. As a result of this action the plunger does not change its position relative to the cylinder 9, and the volume of the chamber 10 is not changed.

It should be observed that during the action of writing, the plunger gradually feeds downward until the end of the piston rod 17 will no longer contact with the ball 34, then automatic feeding of the writing substance ceases, and obviously it is time to refill the pencil. The pencil in this condition is represented in Fig. 6.

During the refilling operation, when the handle part 7 is stripped over the piston rod 17, the tubular casing 26 must be pushed inward by pressing on the end 27; this renders the ball 34 inoperative and permits assembling of these two parts.

For removing the piston 16 from the cylinder 9, the sleeve 31 must be moved in the direction indicated by the arrow 23 relative to the piston, sufficient to render the ball 21 inoperative; this is accomplished by gripping the end 44 of the sleeve, or if the sleeve 31 is so deep in the cylinder 9 so that the end

44 cannot be grasped with the fingers, it is only necessary to turn the pencil so that the sleeve 31 will gravitate in the direction indicated by the arrow 23; the plunger may then be gradually withdrawn from the cylinder 9.

To facilitate a free flow of the writing substance from the hole 43, I provide a needle 45 which is fixed to the tubular point 11 through the fins 46. I prefer to reduce the diameter of the hole 43 as shown at 47, to render the area of the opening around the needle 45 less than the area of the openings 48 between the fins 46. The needle 45 should extend beyond the end of the tubular point 11 as indicated between the arrows 49. This extended needle will maintain a certain space between the opening 47 of the tubular point 11 and the paper, or other material upon which writing is being produced, and thereby permit the writing substance to readily escape from the hole 43.

It is not absolutely necessary to provide a needle 45. This is only desirable in some cases and depends considerably upon the characteristics of the writing substances used with the pencil. For fine neat lines I prefer to eliminate the needle 45, and prepare the writing substance of the proper consistency so that it will flow, when under pressure, through a plain straight hole, like shown at 43 Figs. 5 and 6, in a satisfactory manner. By this arrangement there is little or no opportunity for the writing substance to escape and the writing is produced principally by such quantities which adhere to the paper as a result of rubbing contact. When the needle is employed the diameter of the hole 47 should be somewhat larger to provide the same area of opening and it is then quite impossible to close this opening by bringing the point of the pencil in contact with the paper, particularly if the needle protrudes slightly as indicated between the arrows 49. By this arrangement a greater quantity of writing substance will escape to lay upon the paper and the writing will not be produced so much by the rubbing contact.

However whether or not the needle is employed the lower end of the tubular point 11 should be formed round, or in other words spherical, and polished smooth so that it readily slides over the writing surface. When the needle is employed the lower end thereof should also be formed in similar fashion, and for the same reason, and in no event should the needle 45 protrude beyond the end 42 of the tube to such extend where the tube would not normally touch the writing surface when the pencil is held at the usual angle for writing. Accordingly both the needle and the end 42 of the tube form the writing point of the pencil, both or only either one of the two may be in contact with the writing surface, depending upon the angle at which the pencil is held while writ-

ing. In effect the needle 45 is a continuation of the spherical form of the tube end 42, this most clearly appears in Fig. 2.

It should be understood that the disclosure herein merely represents the preferred embodiment of my invention, and that there might be alternatives for the devices herein described and shown which would not deviate from the scope of the claims.

Having thus described my invention, what I claim and desire to secure by United States Letters Patent is as follows:

1. In a pencil, the combination with a container for semi-fluid writing material provided with an outlet allowing restricted flow therefrom under pressure, of a reciprocable tube leading from said outlet to form the writing point and mounted to the pencil body, and a feeding device capable of forcing said writing material through said tube and operable through inward movement of said tube.

2. In a pencil, the combination with a container for semi-fluid writing material provided with an outlet allowing restricted flow therefrom under pressure, of a reciprocable tube leading from said outlet to form the writing point and mounted to the pencil body, a feeding device capable of forcing said material through said tube and operable through inward movement of said tube, and resilient means arranged to retrieve inward movement of the tube.

3. In a pencil, the combination with a container for semi-fluid writing material provided with an outlet allowing restricted flow therefrom under pressure, of a reciprocable tube leading from said outlet and mounted to the pencil body, and a feeding device for said writing material, said feeding device being arranged to reduce the volume of said container through inward movement of said tube, and to maintain a constant volume in said container during outward movement of said tube.

4. In a pencil, the combination with a container for semi-fluid writing material provided with an outlet allowing restricted flow therefrom under pressure, of a reciprocable tube leading from said outlet and mounted to the pencil body, a piston in said container, and propelling mechanism for said piston, said propelling mechanism being arranged to move said piston forward with forward movement of said tube, and lock said piston against reverse movement.

5. In a pencil, the combination with a reciprocable container for semi-fluid writing material provided with an outlet allowing restricted flow therefrom under pressure and mounted to the pencil body, a piston in said container, and propelling mechanism for said piston, said propelling mechanism being arranged to move said piston forward with

forward movement of said container and lock said piston against reverse movement.

6. In a pencil, the combination with a container for semi-fluid writing material provided with an outlet allowing restricted flow therefrom under pressure, of a piston in said container, a one-way clutch arranged to lock said piston against rearward movement relative to the pencil body, and a tube provided with a centrally perforated but otherwise smooth spherical end for rubbing contact with the writing surface, which communicates with said outlet and forms the writing point of the pencil.
- 15 7. In a pencil, the combination with a casing, of a container within said casing for semi-fluid writing material, and provided with an outlet allowing restricted flow therefrom under pressure and also arranged to slide lengthwise relative to said casing, a piston in said container, and a tube provided with a centrally perforated but otherwise smooth spherical end for rubbing contact with the writing surface, which communicates with said outlet and forms the writing point of the pencil.
- 30 8. In a pencil, the combination with a casing, of a container within said casing for semi-fluid writing material, and provided with an outlet allowing restricted flow therefrom under pressure, and also arranged to slide lengthwise relative to said casing, resilient means arranged to retrieve lengthwise movement of said container, and a tube provided with a centrally perforated but otherwise smooth spherical end for rubbing contact with the writing surface, which communicates with said outlet and forms the writing point of the pencil.
- 45 9. In a pencil, the combination with a casing, of a container within said casing for semi-fluid writing material, and provided with an outlet allowing restricted flow therefrom under pressure, and also arranged to slide lengthwise relative to said casing, a piston in said container, and a one-way clutch arranged to lock said piston against rearward movement relative to said container.
- 55 10. In a pencil, the combination with a casing, of a container within said casing for semi-fluid writing material, and provided with an outlet allowing restricted flow therefrom under pressure, and also arranged to slide lengthwise relative to said casing, a piston in said container, a one-way clutch arranged to lock said piston against rearward movement relative to said container, and a one-way clutch arranged to lock said piston against rearward movement relative to said casing.

- 65 11. In a pencil, the combination with a casing, of a container within said casing for semi-fluid writing material, and provided with an outlet allowing restricted flow there-

from under pressure, and also arranged to slide lengthwise relative to said casing, a piston in said container, a one-way clutch arranged to lock said piston against rearward movement relative to said container, and resilient means arranged to retrieve rearward movement of said container relative to said casing.

12. In a pencil, the combination with a casing, of a container within said casing for semi-fluid writing material, and provided with an outlet allowing restricted flow therefrom under pressure, and also arranged to slide lengthwise relative to said casing, a piston in said container, a one-way clutch arranged to lock said piston against rearward movement relative to said casing, and resilient means arranged to retrieve rearward movement of said container relative to said casing.

13. In a pencil, the combination with a casing, of a container within said casing for semi-fluid writing material, and provided with an outlet allowing restricted flow therefrom under pressure, and also arranged to slide lengthwise relative to said casing, a piston in said container, a one-way clutch arranged to lock said piston against rearward movement relative to said casing, and resilient means arranged to retrieve rearward movement of said container relative to said casing.

14. In a pencil, the combination with the body thereof suitably arranged to form a primary chamber and a secondary chamber, of an auxiliary container for carrying semi-fluid writing material and arranged to fit in said primary chamber, means for transferring said writing substance from said container, while in said primary chamber, to said secondary chamber, a piston in said secondary chamber, mechanism for moving said piston forward, and a tube provided with a centrally perforated but otherwise smooth spherical end for rubbing contact with the writing surface, which communicates with said secondary chamber and forms the writing point of the pencil.

15. In a pencil, the combination with the body thereof suitably arranged to form a primary chamber and a secondary chamber, of an auxiliary container for carrying semi-fluid writing material and arranged to fit in said primary chamber, a piston means for transferring said writing substance from said container, while in said primary chamber, to said secondary chamber, and mechanism operable for moving said piston forward in said secondary chamber.

16. In a pencil, the combination with the body thereof having an opening therein at the writing end, of a container for semi-fluid writing material provided with an outlet al-

lowing restricted flow therefrom under pressure, and mechanism carried by the pencil body and operable through pressure against the surface being written upon for forcing the writing material through said outlet.

6 17. In a pencil, the combination with a container for semi-fluid writing material provided with an outlet allowing restricted flow therefrom under pressure, of means for reducing the volume of said chamber, and reciprocal mechanism mounted to the pencil body and operable through pressure contact with the writing surface to effect a volume reducing action by said volume reducing means.

10 18. In a pencil, the combination with a container for semi-fluid writing material provided with an outlet allowing restricted flow therefrom under pressure, of a reciprocal needle which protrudes from said outlet to form the writing point of the pencil, and feeding mechanism carried by the pencil body and operable to force the material through said outlet through movement of

20 said needle.

25 19. In a pencil, the combination with the body thereof provided with a chamber for semi-fluid writing material, of a tube which forms an outlet for the writing material allowing restricted flow thereof when under pressure, mechanism within said body arranged to create a pressure throughout the writing material, and a needle fixed in the end of said tube and arranged to maintain spaced relation between said outlet and the writing surface.

30 20. In a pencil, the combination of a container for semi-fluid writing material provided with an outlet allowing restricted flow therefrom under pressure, and mechanism carried by the pencil body and operable through pressure against the surface being written upon for forcing the material through said outlet.

35 21. In a pencil, the combination of a container for semi-fluid writing material provided with an outlet allowing the material to escape to the surface being written upon, and mechanism carried by the pencil body and operable through pressure against the surface being written upon for creating a pressure throughout the writing material.

40 In testimony whereof I affix my signature.
BERNARD C. BECKER.
